UNITED STATES PATENT OFFICE.

WILLIAM HARDY, OF PHILADELPHIA, PENNSYLVANIA, ASSIGNOR TO JOHN H. BROMLEY AND EDWARD BROMLEY, COPARTNERS TRADING AS JOHN BROMLEY & SONS, OF PHILADELPHIA, PENNSYLVANIA.

DESIGN FOR A LACE CURTAIN.

No. 39,535.

Specification for Design.

Patented Sept. 8, 1908.

Application filed July 20, 1908. Serial No. 444,550. Term of patent 3½ years.

To all whom it may concern:

Be it known that I, WILLIAM HARDY, a subject of the King of Great Britain, residing in the city of Philadelphia, State of Pennsylvania, have invented a certain new, original, and ornamental Design for a Lace Curtain, of which the following is a specification, reference being had to the accompanying drawings, forming a part hereof, which is a plan view of a lace curtain bearing said design.

I claim—
The ornamental design for a lace curtain, substantially as shown.

WILLIAM HARDY.
